CLAIM

The ornamental design for a massage device as shown and described.

DESCRIPTION

FIG. 1 is a top rear isometric view of a massage device showing the claimed design;

FIG. 2 is a bottom front isometric view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.

The broken lines in the figures show portions of the massage device that form no part of the claimed design.

1 Claim, 6 Drawing Sheets
